UNITED STATES PATENT OFFICE.

MICHAEL GLUCKMAN, OF NEW YORK, N. Y.

BOX FOR FOLDING PAPERS.

1,016,884.

Specification of Letters Patent.

Patented Feb. 6, 1912.

Application filed July 20, 1911. Serial No. 639,537.

To all whom it may concern:

Be it known that I, MICHAEL GLUCKMAN, a citizen of the United States, residing at New York city, in the county and State of New York, have invented certain new and useful Improvements in Boxes for Folding Papers, of which the following is a clear, full, and exact description.

This invention relates to a package containing paper in separate leaves, there being more than one stack of such leaves in the package, and the paper being folded so that upon withdrawing one leaf from a slot in the wrapper of the package the next leaf will have its end brought out, that it may be grasped and removed.

The object of the invention is to provide a simple, cheap wrapper for containing the stacks of paper, separating them one stack from the next, and in providing means for thoroughly inclosing the paper against withdrawal by the use of as little as possible cardboard or heavy paper, of which the wrapper is made.

The scope of my invention will be pointed out in the claim.

In the accompanying drawings: Figure 1 is a view of my improved box before the center portion is glued to the lower portion. Fig. 2 is a transverse sectional view taken through the body of the package as illustrated in Fig. 1, the leaves of paper being shown in elevation. Fig. 3 is a section on the line 3—3, Fig. 1. Fig. 4 is a partial view of Fig. 1 showing the reverse side of the lowest section. Fig. 5 is a section on the line 5—5 Fig. 1. Fig. 6 is a plan view of the scored and cut wrapper. Fig. 7 is a sectional view of three leaves showing how they are folded in the independent stacks.

In carrying out the invention, I provide a number of leaves, one folded as shown in Fig. 7, which is a well known manner of folding, and I place them in two stacks 2 and 3 as shown in Fig. 4. The stacks 2 and 3 are placed on a section 4 of the wrapper of stiff paper or the like, which is provided with apertures or slots 5 and 6, through which one end of the paper of the outer leaf of each stack is passed. I then fold over each stack side wings 7 and 8, each side wing having portions 9 and 10, the portion 9 acting as the outside of the container for each stack, portion 10 for an inside retainer to separate the stacks one from the other as clearly shown in Fig. 2. Each flap

7 and 8 is provided with a slot 11 for engagement with tongues 12 on a bottom flap 13, so that when the side flaps are turned in and the end flap 13 turned over the tongues 60 may enter the slots 11. On the upper side of the portion 4 of the wrapper there are the portions 14 and 15; and the portions 16 and 17, the portions 16 and 17 are of the thickness of the package, the portion 14 being adapted to cover as a back the two wings 7 and 8, when they are in the position of Fig. 1. A daub of glue indicated by irregular lines in Fig. 1 may be applied to the outer side of the wings 7 and 8 to hold 70 the part 14 against them, and thus form an entirely inclosed and un-get-at-able box having two separate chambers for separate stacks of paper. Portion 15 may be folded 75 so as to come in front of the flaps which extend out of the slots, and all these outer sections may contain advertising matter as is common in articles of this character.

In carrying out this invention, details of construction may be varied from those 80 shown, and yet the essence of the invention be retained; some parts might be employed without others, and new features thereof might be combined with elements old in the art in diverse ways, although the herein described type is regarded as embodying substantial improvements over such modifications.

As many changes could be made in the above construction, and many apparently 90 widely different embodiments of the invention could be made without departing from the scope thereof, it is intended that all matter contained in the above description or shown in the accompanying drawings shall 95 be interpreted in an illustrative and not in a limiting sense.

It is furthermore desired to be understood that the language used in the following claim is intended to cover all the generic 100 and specific features of the invention herein described, and all statements of the scope of the invention which as a matter of language might be said to fall therebetween.

I claim as my invention:

A package comprising a section provided with slots adapted for the passage therethrough of leaves of paper, a plurality of foldable portions secured together carried by said section at the upper edge thereof, 110 said foldable portions being adapted to form a cover, a flap carried by the lower

edge of said section, tongues carried by said flap, wings carried by each side edge of said section, said wings being provided with slots adapted to receive the tongues on said flap,
5 and a foldable portion carried by each of said wings, at the outer edge thereof, adapted to form partitions when said package is folded.

Signed at New York city, New York, this 19th day of July, in the year one thousand nine hundred and eleven.

MICHAEL GLUCKMAN.
